UNITED STATES PATENT OFFICE.

WILLIAM A. SLEPPY, OF BERWICK, PENNSYLVANIA.

IMPROVEMENT IN CLOTHES-DRIERS.

Specification forming part of Letters Patent No. 122,071, dated December 19, 1871.

To all whom it may concern:

Be it known that I, WILLIAM A. SLEPPY, of Berwick, in the county of Columbia and State of Pennsylvania, have invented a new and valuable Improvement in Clothes-Driers; and I do hereby declare that the following is a full, clear, and exact description of the construction and operation of the same, reference being had to the annexed drawing making a part of this specification, and to the letters and figures of reference marked thereon.

Figure 1 of the drawing is a representation of a vertical central section of my invention.

This invention has relation to clothes-driers; and it consists in the construction and novel arrangement of a revolving frame or reel having lines upon which to hang clothes, and adapted for expansion and contraction at will, as herein-after described.

Referring to the accompanying drawing, A represents a rounded post provided with an enlarged base, B, and supported in a vertical position by means of legs B'. C C' designate hubs arranged to revolve on the post A, the hub C resting on a shoulder, B, near the upper end thereof. The hub C' is shown located near the lower end of the post, but is capable of being moved up and

down. These hubs are constructed with lugs d d', to which are pivoted or hinged the arms E E' respectively. The outer ends of the arms E E' are hinged together, the former being provided with lugs F, between each pair of which the end of an arm, E', fits. G indicates lines which pass through holes g made in the arms E. These lines are used for the purpose of holding the clothes to be dried.

The drawing shows the clothes-drier expanded ready for use. The arms are folded up, somewhat as the ribs of an umbrella, by moving up the hub C. The base B prevents the hub from falling too low, and thus renders the arms E' self-locking to keep the reel expanded.

I claim as my invention—

The hub C', in combination with the arms E', F, and E, cords G, and enlarged base B, constructed and arranged to operate substantially as specified.

In testimony that I claim the above I have hereunto subscribed my name in the presence of two witnesses.

WILLIAM A. SLEPPY.
